VACUUM CLEANER HANDLE OR THE LIKE

George H. Frost, Ashland, and Robert S. Waters, Lexington, Ohio, assignors to Westinghouse Electric Corporation, a corporation of Pennsylvania

Filed Sept. 22, 1964, Ser. No. 81,831

Term of patent 14 years

(Cl. D9—2)

FIG. 2 is a side elevational view thereof;

FIG. 3 is an end elevational view thereof; and

FIG. 4 is a perspective view thereof.

The broken line showing of the vacuum cleaner is for illustrative purposes only.

We claim:

The ornamental design for a vacuum cleaner handle or the like, substantially as shown and described.
